UNITED STATES PATENT OFFICE.

ARMANDO SALATI, OF PHILADELPHIA, PENNSYLVANIA.

COLLAPSIBLE SEAT.

1,246,791.

Specification of Letters Patent. Patented Nov. 13, 1917.

Application filed July 13, 1917. Serial No. 180,255.

To all whom it may concern:

Be it known that I, ARMANDO SALATI, a subject of the King of Italy, residing in the city and county of Philadelphia, in the 5 State of Pennsylvania, have invented certain new and useful Improvements in Collapsible Seats, of which the following is a true and exact description, reference being had to the accompanying drawings, which 10 form a part thereof.

The object of my present invention is to provide a portable seat of novel construction adapted to be used as an ordinary chair, as a bath tub seat, and in other ways, 15 and especially adapted for use as a sanitary convenience by invalids.

The various features of novelty which characterize my invention are pointed out with particularity in the claims annexed 20 hereto and forming a part of this specification.

For a better understanding of the invention, however, and the advantages possessed by it, reference should be had to the accompanying drawings and descriptive matter in which I have illustrated and described a preferred embodiment of my invention.

Of the drawings:

Figure 1 is a front elevation of my improved seat.

Fig. 2 is a side elevation.

Fig. 3 is a plan view with interchangeable seat cover and back member removed, and

Fig. 4 is a partial rear elevation.

35 In the drawings, A represents the seat body, which, in the preferred form illustrated, resembles a water closet seat of the type in which the seat A proper, is in the form of a horse shoe surrounding the seat opening A' on three sides. The seat body is formed of wood or like material and advantageously, as shown, has secured to its under seat a metallic reinforcing frame B of curved metal angle bars, with bracket 40 arms B' projecting from the supporting frame B at opposite sides of the seat. To the two arms B' at each side of the seat are pivotally connected a pair of arm or leg members C; the two members C of each pair

45 being rigidly connected by a brace C'. Each member C may advantageously be in the form of an iron rod having its upper end flattened and its lower end bent to form a flattened hook C². In the flattened upper 50 end of each member C is formed one or, preferably as shown, more holes C', to re-

ceive the ends of the bolts D by means of which the corresponding pair of members C are pivoted to the brackets B'. Each bolt D passes through the corresponding pair of 60 brackets B', and as shown, through a tubular brace B² connecting the latter. Each bolt D is provided at one end with a head D', and at the other end is threaded to receive a thumb clamping nut B². To secure 65 the members C in positions relative to the seat shown in full lines in Figs. 1, 2 and 4 a swinging latch member E is pivoted to the rear bracket B' at each side of the chair as by means of the rivet E². At its far end 70 each latch member E is provided with a notch E' adapted to take over a headed stud C³ secured to the corresponding member C. In this condition the seat is intended to have the flattened hook end C² of the 75 member C rest upon the floor, or other supporting surface, and the seat may then be used as an ordinary chair. When the latching members E are disengaged from the arms C the latter may be swung into the 80 dotted line positions shown in Fig. 1, in which position the hooked ends C² are adapted to hook over the opposite sides of the bath tub, so that the seat may then be used as an ordinary bath seat.

85 With the particular construction described the latches E will interlock with the studs C³ only when the arms C are in the positions shown in Figs. 1 and 2 with the bolts D passing through the uppermost holes C' 90 in the members C, but when the members C are in their dotted line position the bolts D may pass through whichever of the holes C' will give the most convenient adjustment of the seat with regard to the particular bath 95 tub in which it may then be used. The hooked ends C² of the member C may be covered with rubber tubing, or like material, to prevent the members from marring the surface of the bath tub with which the seat 100 may be used.

A member F, which may be used either to cover the opening A' in the seat proper, or when in the position shown in Figs. 1 and 2, as a back rest, is connected to the seat 105 by hinges F', which should advantageously be of a type to readily permit the separation of the seat and back when this is desirable to facilitate transportation or when it is not desired to use the seat cover. A part F² secured to the member F, operates to engage the seat body and prevent the

member F from turning backward beyond the position shown in Figs. 1 and 2.

Secured to the under side of the seat are supports G for a receptacle H. As shown, 5 the supports G are in the form of parallel angle bars having their horizontal flanges turned toward one another at their lower edges; each support G is secured to the frame work B by rivets G' and G². The 10 receptacle H is formed with a flange H' at its upper end which is adapted to take over the horizontal flanges of the supports G, and may slide into and out of position under the seat.

15 The seat with the receptacle H in place is well adapted for use by an invalid or semi-invalid in washing the portion of his body exposed through the opening A' with washing fluid contained in the receptacle H, 20 which may be dipped up and applied by the hands of the patient. The receptacle H fits snugly against the under side of the seat, and by reason of this fact, and a suitable sloping shape, such as that illustrated, 25 which may readily be given to the receptacle, the liability of the liquid splashing out of the receptacle is greatly minimized.

While in accordance with the provisions 30 of the statutes I have illustrated and described the best form of my invention now known to me, it will be apparent to those skilled in the art that changes may be made in the form of my invention without departing from its spirit, and that some features 35 of my invention may sometimes be used to advantage without a corresponding use of other features of the invention.

Having now described my invention, what 40 I claim as new and desire to secure by Letters Patent, is:—

1. A convertible seat, comprising in combination a seat body and supporting members pivoted to the seat body at its opposite sides and terminating at their free ends in hooks and being adapted to form supporting legs for the seat body when in one position in which said members extend downwardly from the seat body, and being adapted to be swung from said one position into a second position in which said members extend upwardly from the said body and the hook ends thereof are adapted to hook over the opposite sides of a bath tub.

2. A convertible seat, comprising in combination a seat body and supporting members pivoted to the seat member at its opposite sides and terminating at their free ends in hooks, and adapted to be swung from one position in which they extend downwardly from the seat body and form supporting legs for the latter, into another position in which they extend upwardly from the seat body and are adapted to hook over the opposite sides of a bath tub, and means

for releasably locking said supporting members in the first above mentioned position. 65

3. In a convertible seat, the combination of a seat body comprising a metallic supporting frame at its under side including bracket arms projecting at the opposite sides of the seat, supporting members pivoted to said arms and terminating at their free ends in hooks adapted to take over the side edges of a bath tub when said supporting members extend upwardly from the seat, and to engage the floor when said members extend downwardly from the seat, and means for releasably securing said supporting members in rigid relation to said seat body when they extend downwardly from the seat body. 70 75 80

4. In a convertible seat, a seat body provided with bearings at each side edge, a pivot pin mounted in said bearings, supporting members each formed with a series of apertures adapted to receive the corresponding pivot pin, and formed at its opposite end with a hook portion adapted to take over the side edge of a bath tub when said members project upwardly from said seat body, and means for releasably securing said seat 90 body and supporting members in rigid relation when the latter extends downwardly from the seat body. 85

5. In a convertible seat, a seat body formed with an aperture and comprising a 95 metallic frame at its under side at the margin of said aperture, supporting members pivoted to said frame and terminating at their ends in hooks adapted to take over the side edges of a bath tub when extending upwardly from said seat and to engage the floor when extending downwardly from said seat, and a receptacle detachably secured to said frame and having an open upper end in register with the aperture in said seat body. 100 105

6. In a convertible seat, a seat body formed with an aperture open at the front side of the seat and comprising a metallic frame at its under side at the margin of said aperture and including parallel angle 110 bar guides, supporting members pivoted to said frame and terminating at their ends in hooks adapted to take over the side edges of a bath tub when extending upwardly from said seat and to engage the floor when extending downwardly from said seat, and a receptacle slidably received in said guides and having an open upper end in register with the aperture in said seat. 115

7. In a convertible seat, a seat body 120 formed with an aperture and comprising a metallic frame at its under side at the margin of said aperture and including parallel angle bar guides, supporting members pivoted to said frame and terminating at their 125 ends in hooks adapted to take over the side edges of a bath tub when extending upwardly from said seat and to engage the

floor when extending downwardly from said seat, and a receptacle slidably received in said guides and having an open upper end in register with the aperture in said seat.

8. In a convertible seat, a seat body formed with an aperture and comprising a metallic frame at its under side at the margin of said aperture, supporting members pivoted to said frame and terminating at their ends in hooks adapted to take over the side edges of a bath tub when extending upwardly from said seat and to engage the floor when extending downwardly from said seat, and a receptacle detachably secured to said frame and having an open upper end in register with the aperture in said seat body, and a member hinged to said seat body and adapted when lowered to form a cover

for said aperture, and when raised to form a back rest for a person sitting on said seat. 20

9. A convertible seat, comprising in combination a seat body and supporting members pivoted to the seat body at its opposite sides and terminating at their free ends in hooks and being adapted to form supporting legs for the seat body when in one position in which said members extend downwardly from the seat body, said hook ends being flattened to form supporting feet when the members are in said one position, and being 25 adapted to be swung from said one position into a second position in which said members extend upwardly from the said body and the hook ends thereof are adapted to hook over the opposite sides of a bath tub. 30 35
